SUNDIAL

Sigurd Rudholm, Muskegon, Mich.

Application June 25, 1948, Serial No. 147,203

Term of patent 7 years

(Cl. D42—7)

To all whom it may concern:

Be it known, that I, Sigurd Rudholm, a citizen of the United States, residing at Muskegon, in the county of Muskegon and State of Michigan, have invented a new, original, and ornamental Design for a Sundial, of which the following is a specification, reference being had to the accompanying drawings, forming a part thereof.

Figure 1 is a top plan view of a sundial, showing my new design;

Figure 2 is a side elevational view of the same;

Figure 3 is also an elevational view of the same rotated ninety degrees about a vertical axis.

I claim:

The ornamental design for a sundial, as shown.

SIGURD RUDHOLM.
